UNITED STATES PATENT OFFICE.

AUGUST SCHOLER, OF PITTSBURG, PENNSYLVANIA.

LOCK-NUT.

SPECIFICATION forming part of Letters Patent No. 732,590, dated June 30, 1903.

Application filed January 27, 1902. Serial No. 91,364. (No model.)

To all whom it may concern:

Be it known that I, AUGUST SCHOLER, a citizen of the United States of America, residing at Pittsburgh, in the county of Allegheny and State of Pennsylvania, have invented certain new and useful Improvements in Lock-Nuts, of which the following is a specification, reference being had therein to the accompanying drawings.

10 This invention relates to certain new and useful improvements in lock-nuts, and has for its object a device of this character wherein the nut contacting with the object to be locked shall be held in a manner so as to effectually prevent the same from working or jarring loose.

15 My invention has for its further object a device of this character which shall be extremely simple in construction, comparatively inexpensive to manufacture, and highly efficient in its use.

20 The invention further resides in the novel combination and arrangement of parts to be hereinafter more fully described, and specifically pointed out in the claims.

25 In describing the invention in detail reference is had to the accompanying drawings, forming a part of this specification, and wherein like numerals of reference indicate like parts throughout the several views, in which—

30 Figure 1 is an elevation of a bolt, showing my improved lock-nut secured thereto and in central vertical section. Fig. 2 is a plan view of the outer face of the securing-nut. 35 Fig. 3 is a like view of the inner face of the locking-nut.

40 My invention aims to effect an engagement with the securing-nut contacting with the articles to be locked in a manner that when the lock-nut is actuated to form an engagement with the securing-nut the latter will exert greater pressure upon the articles, and thus decrease the liability of the securing-nut and the locking-nut becoming loose. This I obtain by providing the securing-nut 1 on its outer face with a depression or seat 2, arranged eccentrically to the threaded opening 3 in the securing-nut. This depression or seat has its walls tapering inwardly toward the threaded opening and is so arranged that the flat portion 4 will be formed between the walls of the depression or seat and the

threaded opening 3. The outer face of this securing-nut 1 is perfectly flat and is adapted to be engaged by a similar inner face on the locking-nut 5. This locking-nut 5 has the usual threaded opening 6, eccentrically to which is secured the annular bead or ridge 7, the outer walls of which taper toward the peripheral faces of the locking-nut. The bolt being passed through the articles to be locked receives the securing-nut 1, which is then tightened until the desired pressure has been reached, when the locking-nut 5 is placed on the threaded portion of the bolt in a manner as will cause its ridge or bead 7 to engage the seat or depression 4, the nut 5 then being tightened, which will cause the eccentric ridge or bead to contact with the seat or depression and effect a secure engagement. It will be noted that the ridge or bead 7 has its edge slightly rounded, as at 8, corresponding to a like curved portion 9 in the seat or depression. It will also be noted that the taper of the bead or ridge is such as will permit the entire periphery thereof to engage the walls formed by the seat or depression. Thus when the parts are in a locked position the entire periphery of the bead is in contact with the inner circumference of the seat or depression, at which time the inner face of the locking-nut 5 and the outer face of the securing-nut will be found to be in contact.

45 While the accompanying drawings illustrate the most practical form of my invention, still it is obvious that minor changes in the details of construction and combination of parts may be made without departing from the general spirit and scope of the invention.

Having fully described my invention, what I claim as new, and desire to secure by Letters Patent, is—

50 1. In a lock-nut, the combination of a bolt, of a securing-nut provided with a central bolt-opening and having an eccentrically-arranged depression around said bolt-opening, the walls of said depression tapering inwardly to the bolt-opening and having a flat portion formed between the same and the said opening and a locking-nut having an eccentric projection surrounding a central bolt-opening therein, said projection having its outer walls tapered outwardly toward the periphery of said nut and the upper portion of said projection be-

ing flat, said flat portion adapted to be received within the depression of the securing-nut and to engage with the flat portion thereof, substantially as described and for the purpose set forth.

2. In a nut-lock, the combination of a bolt, of a securing-nut provided with a central bolt-opening and having an eccentrically-arranged depression around said bolt-opening, the walls
10 of said depression tapering inwardly to the bolt-opening, the bottom of said depression being flat, and a curved portion formed between the said tapering and flat portions, and
15 a locking-nut provided with a central bolt-opening and having an eccentric projection

surrounding the said opening, the said projection tapering inwardly toward the said opening, the upper portion of the said projection being flat, and a rounded portion connecting the said tapered and flat portions of 20 the said locking-nut, adapted to be received within the said tapered, curved and flat portions of the said securing-nut, substantially as described.

In testimony whereof I affix my signature 25
in the presence of two witnesses.

AUGUST SCHOLER.
